[57] CLAIM

We claim the ornamental design for a vibrator pad, as shown and described.

DESCRIPTION

FIG. 1 is a front elevational view of the vibratory pad of the present invention, with the broken lines showing for illustrative purposes only and form no part of the claimed design; FIG. 2 is a back elevational view thereof;

FIG. 3 is a side elevational view thereof, the sides being mirror images of one another;

FIG. 4 is a top view thereof; and,

FIG. 5 is a bottom view thereof.
